DISPLAY COUNTER

Application filed June 2, 1928. Serial No. 282,495.

This invention relates to a display counter which comprises a number of compartments in which different articles of merchandise are positioned to be displayed, and refers 5 particularly to the form of display counter in which the compartments are formed by detachable glass plates which are adjustable to vary the size of the compartments.

It is an object of the present invention to 10 provide a form of display counter which is of simple construction and which may be readily handled to vary the compartment sizes as desired.

Another object of the present invention 15 is to provide a metal glass or glass holding bracket for such a display counter of simple construction.

Various further objects and advantages 20 of the present invention will appear from the description of the preferred form and example of a display counter embodying the invention. For this purpose, there is hereafter described, with references to the accompanying drawing, the preferred form 25 or example of display counter.

In the drawing:

Figure 1 represents a perspective view of the display counter.

Figure 2 represents an elevation of the 25 metal glass or bracket used in said display counter.

Figure 3 is an elevation of the glass or bracket at right angles to Figure 2.

Referring to the drawings: the display 30 counter comprises a base 2 mounted upon a suitable supporting means 3 of any desired form. The baseboard 2 of the counter is provided at its edges with upstanding walls 4, which form the extreme side walls of the 40 counter. The base 2 and the walls 4 are customarily formed of wood, although it is understood that the invention may not be restricted to the use of any particular materials.

Upon the base 2, are mounted a plurality 45 of counter boards 5, which are generally made of a length extending between the side walls 4 of the display counter and vary in width, in accordance with the width of 50 the compartments of the counter. The

counter boards 5 are preferably provided at their bottoms and adjacent sides of the counter boards, with spacing strips 6, which mount the counter boards on the base 2 with the bottom of the boards spaced above the 55 base 2, so as to permit the boards to be more readily handled.

Between adjacent counter boards 5, a counter is provided with glass plates 7 which extend vertically and are held in position by the adjoining side edges of the counter boards. There are also provided clips or brackets 8, preferably of metal, for holding additional glass plates 9 at right angles to the glass plates 7, for dividing 60 the area of the counter board 5 into display compartments of smaller size and the transverse glass plates 9 and brackets or clips 8, are movable in the display counter structure. 65

For this purpose, the clips or brackets 8 are preferably formed of sheet metal and have a body portion 10 extending vertically, and a base portion 11 turned at right angles thereto, so as to occupy a horizontal position. This base portion is slipped under the counter boards 5 so as to be held by said counter boards or the spacers 6, forming a part of the counter boards, against the base 2 of the display counter, whereby the 70 body portion of the brackets are held in a vertical position, but may be slid along the edges of the counter boards into various positions. The upper end of the body 10 of the clips or brackets is provided with ears 75 12 forming a vertical groove for receiving the edge of the transverse glass plates 9 and supporting these plates in a vertical position.

The construction of the display counter 80 herein described is simple and economical in form and permits all of the members of the counter to be readily removed or replaced. The glass plates and brackets for holding the same to the display counter 85 are held firmly in position without the necessity of employing any devices in the nature of screws or bolts.

While the form of the invention herein disclosed is well adapted to carry out the 90 100

objects of the invention, various modifications may be made, all coming within the invention as defined in the accompanying claim.

5 I claim:

6 A display counter comprising counter boards, vertical plates between abutting edges of the counter boards, plate brackets having base sections extending under the counter boards and having body seat portions forming plate holding grooves and plates transverse to the first-mentioned plates positioned in the grooves of said brackets.

10 15 Signed at Los Angeles, California, this 24th day of May, 1928.

JACK R. RAGLAND.
